GODEL KALENOFF, OF BROOKLYN, NEW YORK

ENVELOPE MOISTENER AND CLOSER

Application filed June 11, 1930. Serial No. 460,507.

This invention relates to an envelope moistener and closer.

An object of the invention is to provide a device of this character which permits the combined operation of moistening and closing the flap of an envelope rapidly and efficiently, so that a large number of envelopes may be closed and sealed in a remarkably short space of time.

10 A further object is to provide means of this character which prevents soiling the hands of the user, and where the operation of moistening and sealing can be made most efficient.

15 With these and other objects in view the invention consists in certain novel features of construction and combinations and arrangements of parts, all of which will be more fully hereinafter described and pointed out in the claim.

In the accompanying drawings, Figure 1 is a perspective view of my improved moistener and font, the position of an envelope being shown in dot and dash lines;

25 Figure 2 is a view in transverse section through the font and through the envelope, showing my improved device in operating position, pressing the flap of the envelope on the moistening surface of the font;

30 Figure 3 is a top plan view illustrating the position of the parts when sealing the envelope flap;

Figure 4 is an end view of my improved tool which performs the pressure function in connection with the moistening and sealing operation; and

Figures 5 is a plan view of the font with the cover removed.

35 My invention has particularly to do with an improved tool illustrated generally by the reference character A, which functions in co-operation with an improved font B to carry out the operation of moistening and sealing an envelope.

40 The tool A, which, of course, may be made of any suitable material, comprises a bar 1 having a handle or grip portion 2 at one end. A wiper plate 3 is fixed to the under face of the bar 2 and is bevelled at one edge, as shown at 4, so as to make the same to slide

freely over the flap of the envelope and force the flap to closing position.

On what may be termed the upper face of the bar 1, a roller 5 is mounted and this roller is preferably of tapering or truncated conical form, and a second roller 6 is mounted at one side of the bar 1. To afford mounting for these rollers 5 and 6 and space them sufficiently from the bar 1, I employ suitable brackets or supports 7 and 8, respectively, 55 on which trunnions 9 on the ends of the respective rollers have free turning movement.

The font B above referred to is supported upon a bar 10 which may constitute a wiper, the front edge of which is bevelled, as shown 65 at 11, so that this bar or base of the font may be used as a wiper as desired, and a handle 12 is fixed to one end of the bar or plate.

The font B is adapted to contain water or other liquid, as illustrated by reference 70 character 13, and a moistening member 14 is supported in the upper portion of the font and has a raised exposure portion 15 which conforms to the general shape or contour of the mucilaged portion of the flap of an envelope. This member 14 has finger-receiving recesses 16, 17, at its edges so as to permit the same to be grasped and reversed, and made to contact with the liquid 13 in the font to moisten the same whenever desired. 75

80 A removable cover 18 is located on the font, and has a slot 19 exposing the raised portion 15 of the moistener. By reason of this arrangement of slot and raised portion of the moistener, a space 20 is provided on the cover receiving that portion of the envelope flap where moisture is not desired, thus supplying a rest for the flap of the envelope while being moistened. An envelope is illustrated generally by the reference character 21, and 85 is provided with the ordinary mucilaged flap 22.

90 In operation, the inner face of the envelope flap is located on the raised portion 15, and the tool A is moved transversely of the font 95 with the rollers 5 and 6 operating to press the mucilaged portion of the envelope flap against the moistening surface so as to apply the necessary moisture to the mucilaged surface. The envelope is then reversed in 100

position, and the wiper 3 is moved transversely of the envelope causing the flap to move downward, and by reason of the pressure of the tool the flap will be neatly and accurately sealed.

The motions of the tool A in carrying out the sealing and closing of the envelope can be easily and quickly performed. The handle 2 of the tool is gripped in the right hand of the user, and by a back-hand motion the rollers 5 and 6 press the mucilaged portion of the flap against the font, and then when the envelope is reversed a movement of the tool in the opposite direction, with the wiper 3 located against the flap, will cause the envelope to be quickly sealed. The operator, therefore, manipulates the envelope with the left hand and with the right hand he manipulates the tool, so that by quick movements the envelope can be readily moistened and sealed.

A device of this character not only functions to perfectly seal the envelope but increases the spread of such operation so that a large number of envelopes may be sealed in a short time.

The roller 5 is preferably tapering, as above stated, so that it readily finds its proper resting place or angular relation to the font in pressing the envelope flap thereon, and the roller 6 constitutes a follower which insures a quick moistening with proper pressure as, of course, it is understood that both rollers are pressing against the envelope flap at the same time.

While I have illustrated what I believe to be the preferred embodiment of my invention, it is to be distinctly understood that various slight changes may be made with regard to the form and arrangement of parts without departing from my invention, and hence I do not limit myself to the precise details set forth but consider myself at liberty to make such changes and alterations as fairly fall within the spirit and scope of the claim.

What I claim is:

A device of the character described comprising a bar adapted to be grasped at one end by the hand of the user, a longitudinally extending roller connected to the bar, and spaced therefrom, a second roller connected to the bar extending longitudinally thereof and spaced from the first mentioned roller, one of said rollers tapering longitudinally and both of said rollers adapted to press an envelope flap against a moistener.

GODEL KALENOFF.
